(57) CLAIM

The ornamental design for lattice panel with corner overlap in hexagonal pattern, as shown as shown and described.

DESCRIPTION

FIG. 1 is a front elevation view of a lattice panel with corner overlap in hexagonal pattern;

FIG. 2 is a bottom view, which is the same as the top view, of the lattice panel with corner overlap in hexagonal pattern;

FIG. 3 is a right side view, which is the same as the left side view, of the lattice panel with corner overlap in hexagonal pattern; and,

FIG. 4 is a rear elevation view of the lattice panel with corner overlap in hexagonal pattern.
